US0D1096774S

(12) **United States Design Patent** (10) Patent No.: **US D1,096,774 S**
Clymer et al. (45) Date of Patent: ** Oct. 7, 2025

(54) **DISPLAY SCREEN OR PORTION THEREOF WITH GRAPHICAL USER INTERFACE**

(71) Applicant: **Apple Inc.**, Cupertino, CA (US)

(72) Inventors: **Andrew Patrick Clymer**, San Jose, CA (US); **William McMillan Tyler**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/877,357**

(22) Filed: **Jun. 5, 2023**

(51) LOC (15) Cl. **14-04**

(52) U.S. Cl.

USPC **D14/485**

(57) **CLAIM**

The ornamental design for a display screen or portion thereof with graphical user interface as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
